UNITED STATES PATENT OFFICE.

FRANZ PAUL EDLER, OF CHICAGO, ILLINOIS.

WINDOW-SCREEN.

1,030,985.

Specification of Letters Patent. Patented July 2, 1912.

Application filed September 14, 1911. Serial No. 649,333.

To all whom it may concern:

Be it known that I, FRANZ PAUL EDLER, a citizen of the United States, residing at Chicago, in the county of Cook and State of Illinois, have invented a new and useful 5 Window-Screen, of which the following is a specification.

This invention relates to window and door screens, and more particularly to means for 10 detachably securing the screen or other material in place on the frame without the aid of tacks or nails.

In carrying out the invention there is provided a screen frame having a marginal 15 groove in one face adjacent the inner edge of the frame, and into which groove the edge of the wire cloth or other fabric is forced and securely held by four angularly bent metallic strips, one edge of which enters 20 said groove and the other edge clamps over the wire. At each of the four corners I employ a corner iron having on its outer edge a depending flange, the lower edge of which terminates in teeth, which are forced into 25 the corners of the frame, after the angle strips are in position, and thus hold the same from working loose.

The invention consists in certain details of construction and combination of parts all 30 of which will be more fully set forth, specially pointed out in the appended claims and illustrated in the accompanying drawing, in which—

Figure 1 is a front view of a complete 35 screen, containing my improvements. Fig. 2 is an enlarged view of a corner of the screen with the corner iron omitted. Fig. 3 is a sectional view on the line 3—3 of Fig. 1 showing the manner of doubling the wire 40 fabric around the angular securing strip. Fig. 4 is a sectional view on the line 4—4 of Fig. 1 showing the manner of securing the angular strips in position by the corner iron. Fig. 5 is an inverted perspective view of the 45 corner iron. Fig. 6 is an inverted perspective view of a portion of the angular strip showing the beveled and straight ends of the same. Fig. 7 is an enlarged view of a corner taken on the reverse side of Fig. 2, 50 showing the position of the joint securing means.

The screen comprises the screen frame 8, the screen fabric material 9, the angular screen securing strips 10, and the metallic 55 corner irons 11.

The screen frame 8 is preferably of wood, and comprises sections beveled at their ends and joined together by suitable fastening means, such as crimped metallic strips 12, 60 adapted to be embedded in the frame sections at the joints, but positioned one on either side of the frame and one at the inner corner and one at the outer corner, thereby forming a rigid joint. The screen frame 8 is provided on one of its faces with a marginal groove 13, which extends completely 65 around the frame between the inner and outer edges thereof, but nearer to the inner edge. It is adapted to receive the inturned edge of the wire screen 9. The grooves meet at the corners of the frame, as will be understood. Between the groove and the inner edge of the frame, the face of the latter is planed down or recessed at 14 in the manner shown very clearly in Figs. 3 and 70 75 4. At the inner edge, the frame is below the outer edge of the frame about equal to the thickness of the screen material, and from the inner edge it slants inwardly toward the groove 13, the recess 14 having its greatest 80 depth at the point of juncture with the groove 13, thus providing a space which when the screen is assembled, permits the respective parts to be flush with the face of the frame. 85

The securing strip 10 is preferably formed from a sheet metal blank, and is angular in cross section, and each strip is preferably of a length sufficient to extend from one corner of the frame to the other. 90 One flange of the strip is adapted to fit into the groove 13, being provided with straight ends, and the other flange is beveled at its ends to provide a miter-joint at the corner of the frame, as shown in Fig. 2. 95

The corner irons 11 are made of sheet metal, preferably sheet steel, and are each formed from a suitable blank, the body of each iron consisting of two limbs 16 and 17 arranged at right angles to each other, each 100 limb being provided along its outer edge with depending, or inwardly extending flanges 18, 19, which stand substantially at right angles to the face of the body portion of the iron, and terminate at their edges in 105 points or teeth, which facilitate the insertion of the corner irons when assembling the screen.

The manner of attaching the wire to the frame is as follows: The frame having been 110

constructed, a piece of screen material 9 is cut of a sufficient size, (preferably one inch longer and one inch wider than the frame), to fill the space defined by the frame and 5 extend over the recess 14 and beyond the groove 13. The inner flange of the angular securing strip 10 at one side is now forced against the screen directly over the groove 13, forcing the screen into the groove as 10 shown in Fig. 3, and causing it to double over the flange. The strip is pressed down into the groove until its outer or top flange comes down upon the screen placed over the frame. This causes the screen and the top 15 or outer flange of the strip to fit flush with the remaining portion of that face of the screen 9 as shown in Fig. 4. This operation having been performed on all sides of the screen causes the securing strips to meet at 20 the corners. The corner irons are now forced into the groove 13 at each corner of the frame, the flanges 18, 19 of the iron being inserted between the outer wall of the groove and the screen material, forcing the 25 screen material and the securing strip more tightly together. The points or teeth of the flanges of the corner iron are of such a length as to penetrate the frame below the base of the groove 13. Thus it will be seen 30 that an efficient screen-securing means has been provided which can be readily attached to or detached from the screen frame, and when attached to the frame all parts lie substantially on a plane with the face of the 35 frame.

The sides of the screen frame may be provided with grooves 22, as in Fig. 2, which are adapted to coöperate with a guide rail carried by a window casing when it is 40 desired to provide a sliding screen.

The feature of importance in this invention lies in the construction of the frame with the continuous marginal groove which is spaced from the inner edge of the frame 45 at all points, that face of the frame through which the groove enters being beveled inwardly from the inner edge of the frame to the said groove, whereby the deepest portion of the bevel is adjacent the groove. As 50 a result of this arrangement, when the securing strips are inserted in the groove, they impart a stretching action to the screen, so that the screen is stretched taut in the open space defined by the inner edges of the 55 frame. Reference being had to Figs. 3 and 4 of the drawing, it will be noted that the outer edge of the screen rests upon the beveled face of the frame, which beveled face commences at the inner edge of the 60 frame and terminates at the groove. It follows that when each strip is inserted in the groove it pulls upon the screen and tightens the same. The difficulty of tightening the screen material in the ordinary 65 construction of window and door screens

is well understood. By this improvement the screen material cannot fail to be made tight in applying the securing strips.

The principal function of the corner irons is to span and cover the space or joint 70 between the meeting ends of the securing strips, and in addition to hold the said strips in place. These corner fastening means are necessary in order to prevent the securing strips from working out from 75 their attached positions.

By the term "screen material" I wish it understood that I do not limit myself to wire screen.

What is claimed is:—

1. In a window or door screen, the combination of a frame, provided with a marginal groove extending into the frame in one face, screen material having its edges received in said groove, angular securing 85 strips having one flange adapted to be forced into the groove and bind the material therein, the other flange clamping the material to the face of the frame, and a corner iron for each corner adapted to be inserted into the groove and secure the angular strips at each corner.

2. In a window or door screen, the rectangular frame having on one face a marginal groove which extends part way through the 95 frame and is carried around the frame continuously so as to intersect at the corners, screen material having its edges received in the said groove, the angular securing strips having one flange extending into the groove 100 and confining the screen therein, the other flange fitting over the screen material and holding it against the face of the screen frame, and corner irons for each corner having depending or inwardly extending 105 flanges which enter the groove at the corners and span the angular strips and serve to hold the latter from displacement.

3. A rectangular frame having in one of its faces a marginal groove extending part way through the frame and between the inner and outer edges of the frame, the space between the groove and the inner edge of the frame being recessed, screen material having its edges inturned and entering the groove, angular securing strips along each side of the frame and meeting at the corners, said strips having their inner flanges entering the groove and confining the screen material therein and having their outer flanges overlapping the screen material and holding it against the face of the frame within the recess of the latter, and corner irons, one at each corner, said corner irons having inwardly bent flanges provided with 115 teeth at their extremities, said flanges of the corner irons being of greater length than the inner flanges of the said strips, whereby when the corner irons are inserted 120 in the groove at the corners, the flanges are 125 130

caused to penetrate the frame beyond the groove, the outer face of the corner irons spanning the securing strips and covering the joint between the same.

5 4. In a window or door screen, a rectangular frame having in one of its faces a marginal groove extending part way through the frame and between the inner and outer edges of the frame, that portion 10 of the face of the screen between the groove and the inner edge of the frame being beveled inwardly, screen material having its outer edges lying upon the beveled face of the frame and received within the groove, 15 securing strips along each side of the frame and meeting at the corners, said strips being adapted to force the edges of the screen material into the groove and retain the same therein, and corner fastenings engaging the 20 meeting edges of the securing strips so as to hold the same in place.

5. In a window or door screen, the combination of a rectangular frame provided with a marginal groove which extends part way 25 through the frame and is carried around the latter continuously so as to intersect at the corners, screen material having its outer edges received in the said groove, angular securing strips along each side of the frame

and meeting at the corners, said strips 30 entering the groove and forcing the screen material therein, and corner fastenings at each corner of the groove adapted to engage the securing strips at the corners and hold the same from displacement. 35

6. In a window or door screen, a rectangular frame having a marginal groove which extends part way through the frame and is spaced from the inner and outer edges thereof, screen material having its outer 40 edges received in said groove, securing strips along each side of the frame and adapted to force the screen material into said groove, and corner irons one at each corner having inwardly bent flanges which 45 are adapted to enter the groove at the corners thereof, and between the outer wall of the groove and the screen, said corner irons being of a sufficient width to span the meeting ends of the securing strips and serving 50 to retain the same within the groove.

In testimony, that I claim the foregoing as my own, I have hereto affixed my signature in the presence of two witnesses.

FRANZ PAUL EDLER.
